UNITED STATES PATENT OFFICE.

THOMAS M. LILLISTON, OF SUFFOLK, VIRGINIA, ASSIGNOR TO NATIONAL MACHINE CORPORATION, OF NANSEMOND, VIRGINIA, A CORPORATION OF VIRGINIA.

ROTARY PEANUT-STEMMER.

1,103,305.

Specification of Letters Patent. Patented July 14, 1914.

Application filed January 9, 1914. Serial No. 811,214.

To all whom it may concern:

Be it known that I, THOMAS M. LILLISTON, a citizen of the United States, and a resident of the city of Suffolk, in the county of 5 Nansemond, State of Virginia, have invented certain new and useful Improvements in Rotary Peanut-Stemmers, of which the following is a specification.

This invention relates broadly to mechanisms for use in the peanut industry and more particularly to a mechanism especially designed for stemming peanuts and analogous uses.

The principal object of this invention is 15 to provide a mechanism for stemming peanuts wherein the peanuts undergo a cleaning and polishing action within the stemming mechanism.

Another object of this invention is the 20 production of a mechanism for subjecting unstemmed peanuts to attrition during the stemming process.

A further object of this invention is the 25 production of a self-contained peanut stemmer comprising a receptacle for the peanuts and stemming saws coöperating with the receptacle and wherein the stemming saws and the receptacle are mounted upon a removable frame in such manner as to constitute 30 a unitary mechanism.

A still further object of this invention is 35 to provide a peanut stemmer wherein the peanuts are subjected to a progressive movement in the nature of a slowly advancing spiral path wherein the nuts are successively brought into the paths of the stemming saws.

Other and further objects of this invention will in part be obvious and will in 40 part be pointed out in the specification hereinafter following by reference to the accompanying drawings wherein like characters represent like parts throughout the several figures thereof.

Figure 1 is an elevational view of the 45 stemming drum and stemming saws. Fig. 2 is a sectional view of the drum and stemming saws taken on substantially a horizontal plane as indicated by the line A—A, Fig. 50 4. Fig. 3 is a detail end view of a portion of the mechanism. Fig. 4 is a view, showing 55 details of the drum and stemming saws, wherein certain parts are illustrated in section. Fig. 5 is a detail view of a part of one of the stemming saws. Fig. 6 is a view

indicating the arrangement and construction of parts wherein the entire stemming device is self-contained in the nature of a unitary structure. Fig. 7 is a diagrammatic view illustrating the path of the peanuts while in the zone of the stemming saws.

The art relating to peanut stemmers shows it to be old to use as a stemmer, a cylindrical stemming drum arranged on a horizontal axis, wherein the stemming drum 60 comprises a plurality of pulleys having non-foraminous peripheries, spaced apart to provide circumferential slots, and a single set of stemming saws extending within the drum through the slots, and wherein the 65 stemming saws are rotated to maintain a peripheral speed less than the peripheral speed of the drum. Such constructions have not proven practical since the unstemmed peanuts will not properly feed through the 70 drum, and since stems broken off within the drum can only escape through the circumferential slots, thereby imposing so much work upon the stemming saws as to render 75 them incapable of effectually performing 80 their normal functions. Furthermore, experiment has shown that a single set of stemming saws coöperating with a stemming drum having a peripheral speed equal to, or greater than, the peripheral speed of the 85 stemming saws, will not effectually stem peanuts because the greater speed of the drum has the tendency of carrying the unstemmed pods over the saw teeth, thereby 90 preventing the stems from catching between the teeth.

Applicant's device which will hereinafter be described in detail by reference to the drawings, has by extended practical and commercial use been shown to overcome the 95 difficulties above specified with reference to the known prior art of peanut stemmers.

Applicant's device comprises a self-contained or unitary group of mechanism, 100 which includes a long drum of which substantially the one-half portion is an inclined rotating sieve, and the remaining one-half includes the stemming portion proper made up of short sections of cylinders formed of perforated metal. The whole drum is mounted on an inclined axis and is provided with a relatively small inlet opening at the receiving end, which opening is substantially entirely inclosed 105 110

by an inlet trough, and is provided with a relatively large outlet opening at the discharge end of the drum. The outlet opening is of such size that the discharge end 5 of the drum is provided with an annular ring whose width is greater than the greatest width of the stemming saws extending within the drum. This construction insures that the stemming saws, during operation, 10 will have their peripheries substantially covered by peanuts. The mid portion of the drum is provided with an annular gear which meshes with a pair of small pinions mounted upon their respective stemming 15 saw shafts. The bearings for the stemming saw shafts are fixedly attached to the frame work that carries the stemming drum in such manner that the entire mechanism is self-contained. The diameter of the stemming 20 saws is substantially twice the diameter of their driving pinions, so therefore the peripheral speed of the stemming saws is substantially twice the peripheral speed of the drum, since the peripheral speed of 25 the pinions is substantially the same as the peripheral speed of the drum. The lower stemming saw shaft is preferably located to one side of the vertical line bisecting the drum and on the side in the direction 30 of the rotation of the drum. The upper stemming saw shaft is located farther up on the periphery of the drum so that the saws carried thereby are beyond the zone of action of the first set of saws on the 35 lower shaft. The construction and arrangement of this drum is such that the unstemmed peanuts undergo an attriting action in the screen part of the drum whereby the majority of the dirt is removed and the 40 shells to a certain extent are polished, and small sticks, parts of vines, leaves and trash are also removed before the stemming saws are reached. The longitudinal slots in the sieve portion have a tendency to 45 direct the peanuts in a longitudinal direction thus arranging the pods to be acted on most effectively by the stemming saws. The reticulated metal work comprising the stemming drum portion, permits stems 50 which are cut within the drum to drop through the openings and thereby relieving the stemming saws of a large amount of ineffective work. By the inclination of the cylinder, and because of the small inlet 55 opening and the large outlet opening, the peanuts have a normal travel from the inlet to the discharge end, in a modified spiral path. The forces acting within the effective zone of the stemming saws however, 60 are such as to be substantially centered or counter-balanced at a location between the stemming saws so that the majority of the peanuts are carried to this field by the various opposing forces and consequently are 65 rotated over and over in this zone until the

stems are caught in the teeth of the saws and pulled off.

Referring now to the drawings, a relatively long drum 1 is mounted for rotation upon the drum shaft 2 which is supported 70 in journal brackets 4 that are mounted on the end sills of the main frame 5 (Fig. 6). The drum 1 is preferably formed in two sections, each of which is substantially one-half the total length of the drum. The first 75 section A preferably includes an inlet header 6 which has its end wall 7 inclined and is provided with a relatively small inlet opening 8 that is substantially closed by an inlet spout 9. This first section A also includes a 80 cylinder 10 formed of sheet metal and provided with slots 11, the major dimension of which is substantially parallel to the axis of the drum. Flights or beaters 12, comprising boards or plates of sheet metal, are secured 85 within the cylinder 10 by means of brackets 14 which are riveted or bolted through the cylinder 10. The second section B of the long drum 1, is composed of a series of 90 pulleys C which have their peripheries spaced apart a sufficient distance to provide circumferential slots 15. These pulleys include spiders 16 upon which are mounted the face or peripheral portions 17 of the pulleys, which face is preferably formed of 95 sheet metal provided with slots 18, whose major direction extends in the direction of the circumference of the pulleys. Intermediate the first and second section is an annular member 19 which forms a support for 100 one end of the cylinder 10 and which is provided on its periphery with a large annular gear 20. The discharge end of the drum is provided with an outlet header 21, which is provided with a relatively large 105 outlet opening 22. The outlet header has its periphery provided with sprocket teeth 24 thereby providing a large sprocket wheel by means of which the drum as an entirety 110 may be rotated by suitable driving mechanism (see Fig. 3) which as illustrated, includes the sprocket chain 25, and the small sprocket wheel 26 that is mounted on the shaft 27. The drum 1 may of course be driven by any suitable driving mechanism, 115 but in the construction disclosed, the shaft 27 is mounted in journals on the peanut picking and stemming machine frame 28 and carries a bevel gear 29 which is driven by a companion bevel gear 30 mounted upon 120 the driving shaft 31. The main frame 5 (Figs. 1, 3, 4 and 6) carries arch-shaped bearing plates 32 in which are journaled the stemming saw shafts 34 and 35. These saw 125 shafts are provided with pinions 36 and 37 respectively, which engage the large annular gear 20 thereby rotating the stemming saw shafts 34 and 35 when the large drum 1 is rotated. The stemming saw shafts 34 and 35 carry respectively a series of stemming 130

saws 38, and a series of stemming saws 39. These stemming saws are arranged to project through the circumferential slots 15 between the pulleys C in such manner that there is one saw of the series 38 and one saw of the series 39 in each circumferential slot 15. By inspection of Fig. 4 it will be noted that the stemming saw shaft 34 is arranged to the left of a vertical line passing through the axis of the drum 1 and that the stemming saw shaft 35 is arranged in such manner that the saws 39 carried thereby are somewhat above and beyond the zone of action of the saws carried on the shaft 34, and that the peripheral speed of the stemming saws is approximately twice the peripheral speed of the stemming drum.

Any suitable mechanism may be provided for disposing of the peanuts after they have passed out of the discharge end of the stemming drum 1, but in the construction herein shown a two bladed paddle is provided. This paddle comprises a spider 40 on each arm of which is riveted or otherwise secured, a paddle blade 41 preferably formed of a thick piece of rubber belting. The peanuts passing through the discharge opening 22 drop into the trough 42 and are swept out into the outlet spout 44, indicated in Fig. 3 in dotted lines.

As will be noted from Figs. 1 and 6, the entire mechanism is mounted upon its own individual frame in such manner as to be self-contained and thus may be assembled without reference to assembling of other mechanisms with which it may be used in co-operative relation, as for example a peanut picking device. (Not shown.) By Fig. 3 however, it will be noted that preferably the main frame 5 is securely clamped or held in position on the cross bars 45 (only one of which is illustrated) of the peanut picking and stemming machine frame. Clamping blocks 46 are bolted on the cross bars 45 and engage with the main frame 5 to securely hold the stemmer in position.

By reference to Fig. 5 it will be noted that the points 47 of the stemming saws are slightly rounded and that the gullets are also rounded sufficiently to prevent the wedging of peanut stems between the saw teeth.

In the operation of the device, unstemmed peanuts passing down the inlet spout 9 and down the inclined wall 7 of the inlet header 6 into the cylinder A have a tendency to travel toward the outlet end of the drum 1 because of the inclination of the axis of the drum 1 to the horizontal, as hereinbefore specified. As the drum rotates the unstemmed peanuts are tumbled and successively lifted by the flights 12 and drop, thus substantially removing all of the loose earth and dirt that adheres to the shells, and the action of the longitudinal slots 11 together

with the longitudinal flights 12 arranges the peanuts in such manner that their greatest length is substantially parallel to the axis of the drum, consequently by the time the peanuts reach the stemming section B 70 they are positioned to most efficiently cooperate with the stemming saws.

By reference to Fig. 7 it will be noted that there are three forces acting upon the peanuts within the stemming section B, one 75 force being the rotation of the large drum 1, another force being the series of saws 38 and 39, and the third being the force of gravity. Such peanuts as rest upon the stemming drum will be carried upward along 80 the line of the arrows M. Peanuts whose stems are caught by the saw teeth of the saws 38 will be carried as indicated by the arrows N, and will to a certain extent, carry the surrounding peanuts in the same general 85 direction, and the two forces M and N tend to deliver the peanuts at the zone O. Such peanuts as pass between the saws will continue to travel in the direction of the arrows M, and such peanuts as are caught by the 90 saws 39, and whose stems are not removed until the saw passes beyond the periphery of the drum 1, will move in the path indicated by the arrows P. After the forces M and P are counteracted by the force of 95 gravity, the upper portion of the nuts will roll downward in the general direction of the arrows R, until the downward force is overcome by the forces M and N.

From an inspection of the diagrammatic Fig. 7, it will be noted that the general tendency of the forces, as indicated by the majority of the arrows, is toward the zone O. Since the zone O is between the stemming saws 38 on one side and the stemming saws 39 on the other side, it will be noted that this is the most effective stemming zone in the whole drum and therefore it will be seen that the arrangement and construction of parts is such as to effectively make use of 100 this fact, since the majority of the peanuts are carried to and agitated within this zone. The stemmed peanuts naturally have a freer movement than the unstemmed peanuts, so that the stemmed pods gradually move toward 105 and pass out the discharge opening and out into the outlet trough.

Having thus described my invention what I desire to claim is:—

1. In a peanut stemmer in combination, a 120 rotary drum including a portion provided with elongated openings substantially parallel to the axis of the drum adapted to arrange the nuts longitudinally in the drum when said drum is rotated, and a stemming portion comprising short cylinders spaced apart to form circumferential slots, stemming saws extending through said circumferential slots into the interior of said drum, means to rotate the drum, means to rotate 125 130

said saws, and means for supplying peanuts to said drum, said parts being adapted and arranged to cause said peanuts within the drum to be discharged therefrom.

5 2. In a peanut stemmer in combination, a rotary drum including a portion adapted to arrange the peanuts lengthwise in the drum prior to their arriving at the stemming mechanism, and a stemming portion 10 comprising short cylinders spaced apart to form circumferential slots, stemming saws extending through the slots into the interior of the drum, and an inlet chute for supplying peanuts to the drum, said parts being 15 adapted and arranged to cause the peanuts within the drum to be discharged therefrom.

3. In a peanut stemmer in combination, a rotary stemming drum comprising a plurality of short cylinders spaced apart to 20 form circumferential slots, the periphery of each cylinder being provided with a plurality of elongated openings having their major dimension parallel to said circumferential slots, stemming saws extending 25 through said slots into the interior of said drum, means to rotate said stemming saws when said drum is rotated, and means for introducing peanuts into said drum, said parts being constructed and arranged for 30 causing peanuts to be discharged from said drum.

4. In a peanut stemmer in combination, a rotary drum including a sieve portion provided with elongated openings substantially parallel to the axis of the drum adapted to arrange the nuts longitudinally in the drum, and a stemming portion comprising short cylinders spaced apart to form circumferential slots, a plurality of stemming 35 saws extending through each slot into the interior of the stemming portion, and means to supply peanuts to the drum, said parts being adapted and arranged to cause peanuts to be discharged from the drum.

45 5. In a peanut stemmer in combination, a rotary drum including short cylinders spaced apart to form circumferential slots, means to rotate said drum, stemming saws extending through said slots into said drum, a shaft upon which said stemming saws are 50 mounted, a large annular gear carried by said drum and rotatable therewith, a small pinion of less diameter than said stemming saws and mounted on said saw shaft in engagement with said annular gear to drive said saw shaft when said annular gear is rotated, and means to supply peanuts to said drum, said parts being adapted and arranged to cause said peanuts to be discharged from the drum.

60 6. In a stemming mechanism in combination, a rotary drum including short cylinders

ders spaced apart to form circumferential slots, means to rotate said drum, stemming saws extending through said slots into the 65 interior of said drum, shafts upon which said stemming saws are mounted, said shafts being arranged at substantially the same distance from the periphery of the drum and one shaft being arranged above the other, a 70 large annular gear carried by said drum, a pinion on each shaft in engagement with the large annular gear, and means to introduce peanuts into said drum, the parts being constructed and arranged to cause said 75 peanuts to be discharged from the drum and to cause the zone of maximum activity to lie between the series of stemming saws.

7. In a peanut stemmer in combination, a drum comprised of short cylinders spaced apart to form circumferential slots, a shaft 80 parallel to the axis of said drum, stemming saws mounted upon said shaft and extending into said drum through said slots, means to rotate said drum, means carried by said 85 drum to rotate said shaft when said drum is rotated, and means to introduce peanuts into said drum, the parts being adapted and arranged to discharge peanuts from said 90 drum.

8. In a peanut stemmer in combination, an inclined rotating drum adapted to arrange a mass of unstemmed nuts with the major dimension of the majority of the nuts 95 extending substantially lengthwise of the drum and to feed the mass of unstemmed nuts to stemming devices, stemming devices including a gang of stemming saws having their blades set transverse the path of the mass of unstemmed nuts, and means to rotate 100 said stemming saws.

9. In a peanut stemmer in combination, a rotary drum comprising short cylinders spaced apart to form circumferential slots, two stemming saws arranged in each slot, 105 the axes of the saws being on the same side of a vertical plane through the axis of the drum and below a horizontal plane passing through the axis of the drum, means to rotate said drum so that the bottom thereof moves toward said stemming saws, means to rotate the stemming saws in a direction opposite to the rotation of said drum so that the top of the saws rotate in the same 110 general direction as the bottom of the drum, and means to introduce peanuts into said drum, the parts being adapted and constructed to discharge peanuts from said 115 drum.

THOMAS M. LILLISTON.
